UNITED STATES PATENT OFFICE

160,044

GAS HEATER

Joseph Newman White, Atlanta, and Jay Fred King, Marietta, Ga., assignors to The Atlanta Stove Works, Inc., Atlanta, Ga.

Application March 23, 1949, Serial No. 1,565

Term of patent 14 years

(CL. D81—10)

To all whom it may concern:

Be it known that we, Joseph Newman White and Jay Fred King, both citizens of the United States of America, and residing respectively at Atlanta, in the county of Fulton and State of Georgia, and Marietta, in the county of Cobb and State of Georgia, have invented a new, original, and ornamental Design for a Gas Heater, of which the following is a specification, reference being had to the accompanying drawing, forming a part thereof.

In the drawing,

Figure 1 is a perspective view of a gas heater, showing my new design,

Figure 2 is a top plan view,

Figure 3 is a rear elevational view,

Figure 4 is a side elevational view.

We claim:

The ornamental design for a gas heater, as shown.

JOSEPH NEWMAN WHITE.
JAY FRED KING.
